UNITED STATES PATENT OFFICE.

WILLIAM J. BOHAN, OF ST. PAUL, MINNESOTA.

CAR-DOOR LOCK.

1,095,792.

Specification of Letters Patent.

Patented May 5, 1914.

Application filed October 17, 1912. Serial No. 726,396.

To all whom it may concern:

Be it known that I, WILLIAM J. BOHAN, a citizen of the United States, residing at St. Paul, in the county of Ramsey and State 5 of Minnesota, have invented certain new and useful Improvements in Car-Door Locks; and I do hereby declare the following to be a full, clear, and exact description of the invention, such as will enable others skilled 10 in the art to which it appertains to make and use the same.

My invention relates particularly to locks for the sliding side doors of box cars, and has for its object to provide means rendering 15 it impossible to remove the lock elements by manipulation with the bolts used to secure the same in working position.

Generally stated, the invention consists of the novel devices and combinations of devices hereinafter described and defined in the claims.

Locks of the character indicated usually comprise a pivoted lock piece on the car door, and a coöperating lock bracket on one 25 of the door posts, and these are customarily secured to respective parts noted, by means of nut-equipped bolts. When the door is locked, the car seal is customarily applied to secure the lock piece and bracket in interlocking engagement, and the seal when applied is intended to indicate that the lock has not been tampered with and that the door has not been opened, so as to permit 30 of the removal of the goods from the car. However, it has been found to be a common 35 practice of so-called box car thieves to leave the car seal intact and to have gained access to the car by removal of one or more of the bolts of the lock. When this is done, the 40 parts of the lock may be replaced so that an inspector finding the seal intact will usually pass the lock as in good condition, and it, therefore, becomes extremely difficult to determine just where the lock was tampered 45 with. Until the place where the car breaking has taken place can be determined, it is impossible to discover the perpetrators. As already indicated, this invention provides means for protecting the lock securing bolts 50 so that they cannot be removed or loosened from the exterior of the car.

In the accompanying drawings which illustrate the invention, like characters indicate like parts throughout the several 55 views.

Referring to the drawings, Figure 1 is a fragmentary view in side elevation showing my invention applied to a lock and illustrating the lock applied to a car, some parts being broken away; Fig. 2 is a horizontal 60 section taken on the line $x^2 x^2$ on Fig. 1; Fig. 3 is an elevation showing one of the door posts and the lock bracket applied thereto, and looking at the same in a direction from the right toward the left in respect to Figs. 1 and 2; Fig. 4 is a side elevation of the lock bracket removed from the door post, some parts being broken away; Fig. 5 is a section taken approximately on the line $x^5 x^5$ on 70 Fig. 4, and showing also the door post in horizontal section; Fig. 6 is a horizontal section taken through a portion of the car door and showing the pivoted lock piece applied thereto; Fig. 7 is a detail in section on the 75 line $x^6 x^7$ on Fig. 6; and Fig. 8 is an elevation looking at the inner face of the pivoted lock piece.

The numeral 1 indicates a portion of one side of the car, the numeral 2 the adjacent 80 door post and the numeral 3 the sliding side door.

The numeral 4 indicates a lock bracket which is rigidly bolted to the door post 2, and the numeral 5 indicates the pivoted 85 lock piece which is pivotally applied to the door 3. The lock piece 5, at its free end, is provided with a laterally projecting lock flange 6 and channel 7 that are engageable, respectively, with a lock channel 8 and lock 90 rib 9 formed on the said lock bracket 4. The lock bracket 4 and lock piece 5 are provided with perforated lugs 10 and 11, respectively, through which a car seal 12 is adapted to be applied, as shown in Fig. 1, to thereby 95 hold the said lock piece against pivotal movements in respect to the said lock bracket. Obviously, when the lock piece 5 is held against pivotal movements in respect to the lock bracket, the door 3 will be locked 100 in a closed position.

The lock piece 5 is pivotally connected to the door 3 by a nut-equipped bolt 13, the head of which is located at the outer side of the door. The said bolt is passed through 105 a long sleeve-like hub 14, preferably cast integral with the lock piece 5, and the head of the said bolt is covered by an arched web 15 that completely covers the same. The insertion of the bolt into the sleeve-like hub 110

14 is made possible by a lateral entrance passage or slot 16 cut in one side of the said sleeve, and extended outward through one side of the inner portion of the lock piece 5 (see particularly Fig. 7). The head of the bolt, when the bolt is alined with the axial passage of the sleeve 14 is pressed inward into a seat formed back of a lock flange 17 which cuts off access to the inner face of the 10 bolt head and to the body of the bolt. The sleeve 14 is directly seated in the metal bushing 18 which is set into and is extended through the door 3. The nut 13^a of the bolt 13 clamps a washer 19 directly against the 15 inner end of the sleeve-like hub 14. Thus it will be seen that when the bolt is applied, as just described, and as best shown in Figs. 6 and 7, it will be impossible to cut off the bolt head from the exterior of the car, or to 20 otherwise tamper with the outer end of the bolt. Preferably, the bolt 13 is provided with a square shank 13^b which fits the square seat in the hub 14 and holds the said bolt against rotation in respect to the said sleeve. 25 This same principle of construction may be carried out in all of the bolts used to secure the lock bracket 4 to the door post, but, as shown, it is applied to only one of the said bolts, to-wit, to the bolt 20, two of the bolts 30 21 being also employed to secure the said brackets to the said post. In this arrangement, the head of the bolt 20, which is at the outside of the car, is covered and protected by an arch web or flange 22, shown as cast 35 integral with the said bracket 4. To permit the bolt 20 to be applied to the base of the said bracket, the latter is provided with a lateral entrance passage 23 (see particularly Figs. 4 and 5), and is provided with a rib 40 24 which prevents a chisel or other instrument from being driven between the bolt

head and the base flange or web of the said bracket 4.

By the above described simple expedients, any desired number or all of the bolts used 45 to secure the lock elements to the car body or door post and to the door may be secured in such way that their heads cannot be cut off. This makes it absolutely necessary to break the car seal in order to open the car 50 door.

What I claim is:

1. The combination with a car body and door, of a lock bracket and coöperating lock piece, bolts securing said bracket to the car 55 body, said lock piece having a sleeve-like hub seated in said door, and a bolt seated in said sleeve-like hub and pivotally connecting said lock piece to said door, said hub having a lateral entrance passage in said bolt extending from end to end thereof, and said lock piece having a web covering the head of said bolt.

2. The combination with a car body and door, of a lock bracket and coöperating lock 65 piece, bolts securing said bracket to the car body, said lock piece having a sleeve-like hub seated in said door, and a bolt seat in the said sleeve-like hub and pivotally connecting said lock piece to said door, said hub 70 having a lateral entrance passage for the said bolt and the said pivoted lock piece having a web covering the head of said bolt and having a guard rib or shoulder projecting outward beyond the inner face of the bolt 75 head, substantially as described.

In testimony whereof I affix my signature in presence of two witnesses.

WILLIAM J. BOHAN.
